UNITED STATES PATENT OFFICE

JACK B. MAPLES, OF MIDDLESBORO, KENTUCKY

POWER HOIST CURTAIN

Application filed December 27, 1930. Serial No. 505,337.

This invention relates to a power hoist curtain particularly adapted for use on locomotive cabs, and has for its primary object to provide, in a manner as hereinafter set forth, a curtain of such character which may be quickly raised from within the cab by merely turning a valve, thereby providing an element of safety for the occupants of the cab in the event of a wreck or the like.

10 A further object of the invention is to provide a power hoist curtain of the character aforesaid, the operation of which will not be affected by strain caused by curves in the track.

15 A further object of the invention is to provide a power hoist curtain of the character aforesaid which is maintained entirely out of the way when the curtain elements are in open position, and therefore which need not be removed during the seasons of the year in which the curtain elements are seldom or never needed.

20 With the foregoing and other objects in view, the invention consists of the novel construction, combination and arrangement of parts as hereinafter more particularly described, and as illustrated in the accompanying drawings wherein is shown an embodiment of the invention, but it is to be understood that the description and drawings are to be taken as illustrative and that the invention is intended to be limited only by the scope of the claims hereunto appended.

25 In the accompanying drawings in which like numerals are employed to designate like parts throughout the several views:

30 Figure 1 is a sectional side elevation showing a power hoist curtain in accordance with this invention in applied position with respect to a locomotive cab.

35 Figure 2 is an enlarged fragmentary section taken on the line 2—2 of Figure 1.

40 Figure 3 is a vertical transverse section taken at a point indicated by the line 3—3 of Figure 1.

45 Figure 4 is an enlarged sectional elevation through the pressure cylinder and associated parts.

50 Figure 5 is an enlarged section taken on the line 5—5 of Figure 4.

Figure 6 is a top plan of a modified form of pressure cylinder and associated parts.

Referring to the drawings in detail, the numeral 1 indicates generally a locomotive cab having the usual side openings 2 which are adapted to be closed by means of a pair 55 of curtain elements 3 forming a part of the present invention.

The curtain elements 3 may be formed of any suitable flexible material and are provided adjacent their lower edges with oppositely disposed anchor members 4 formed at their outer ends with spherical heads 5 which are adapted to slide within slotted guide elements 6 secured to the walls of the 60 openings 2. The guide elements 6 are of cylindrical construction and are flared at their upper ends as indicated at 7 to permit the ready insertion of the heads 5 thereinto. While the heads 5 are shown as spherical, 65 and the guides 6 as cylindrical, the heads and guides might be of any other suitable, corresponding shape.

The curtain elements 3 are secured at their upper ends to drums 8 which are preferably 70 formed with reduced end portions 9. Each of the drums 8 is fixedly mounted on a shaft 10 extending therethrough, the shaft being rotatably supported in a pair of brackets 11 secured to the cab 1. Each of the shafts 75 10 on which the drums 8 are mounted is provided at one end with a pulley 12 which is mounted for rotation with the shaft.

Suitably connected with the cab 1, by means of brackets 13, is a pressure cylinder 14 having one end thereof connected with an air pressure line 15 provided with a cut off valve 16 and further provided with an exhaust valve 17 located between the valve 16 and the cylinder 14. Slidably mounted 80 within the cylinder 14 is a piston 18 which is fixedly secured to a piston rod 19 slidably extending through a stuffing box 20 formed on the end of the cylinder 14 opposite the air line 15. The piston rod 19 is flattened 85 at its outer end as indicated at 21, the flattened outer end being fixedly secured to a substantially U-shaped supporting member 22 for a stub shaft 23 which is journaled in 90 and extends through the supporting mem- 95

ber. Fixedly mounted on the shaft 23, between the legs of the member 22, is a gear 24, the teeth of which mesh with the teeth of a rack 25 supported by brackets 26 secured to the cab 1. Depending from the supporting member 22 is a guide bracket 27 which is suitably formed to receive a lower portion of the rack 25 therein, the guide bracket 27 serving to steady the member 22 with respect to the rack 25.

Fixedly mounted on the stub shaft 23 is a double pulley 28 to which is connected a pair of chains 29 and 30 respectively. The chain 29 passes over an idler pulley 31 rotatably mounted on a stub shaft 32 journaled in a bracket 33 secured to the cab 1. From the idler pulley 31, the chain 29 extends to the pulley 12 on one of the shafts 10 and is fixedly secured to such pulley. The chain 30 extends from the pulley 28 to the pulley 12 on the opposite shaft 10 and is fixedly secured to such pulley. The chains 29 and 30 extend over the pulleys 12 in an outward direction and have portions thereof wound over the pulleys.

In Figures 1 and 3, the curtain elements 3 are shown in closure position, in which position the piston 18 will be located adjacent the end of the cylinder 14 connected with the air line 15, and the valves 16 and 17 will be closed. If it is desired to elevate the curtain elements 3 to open position, the valve 16 is opened to provide for the admission of compressed air or the like into the cylinder 14 in order to move the piston 18 longitudinally of the cylinder. Upon movement of the piston 18, the gear 24 is moved along the rack 25 and the chains 29 and 30 are wound on the pulley 28 simultaneously with the unwinding of the chains from the pulleys 12. The unwinding of the chains from the pulleys 12 cause the drums 8 to be rotated in a manner to wind the curtain elements 3 thereon. The ratio of the gear 24 to the strokes of the piston 18 is such that the curtain elements 3 will be elevated by one stroke of the piston operating in a relatively short cylinder. So long as the valve 16 remains open, and the valve 17 remains closed, the air pressure within the cylinder 14 will maintain the curtain elements in their open or raised position.

If it is desired to lower the curtain elements 3, the valve 16 is closed and the valve 17 is opened to relieve the pressure within the cylinder. After the pressure within the cylinder has been relieved, the curtain elements 3 may be readily moved to closure position manually, after which the valve 17 is again closed in order that the device may again be operated to elevate the curtains by opening the valve 16. Adjacent the opposite end thereof from the pressure line 15, the cylinder 14 is provided with an exhaust port 14', in order that any excess pressure within

the cylinder may escape to prevent undue strain on the cylinder.

Instead of employing the gear 24 and rack 25 in connection with a relatively short cylinder such as 14, a relatively long cylinder such as shown at 34 in Figure 6 may be employed. The employment of a long cylinder such as 34 also necessitates the employment of a relatively long piston rod 35 in order that the piston 36 may move throughout the length of the cylinder 34. When this form of cylinder and piston rod is employed, preferably the piston rod will have fixedly connected thereto a bracket 37 which is slidably supported within a suitably mounted guide 38 disposed beneath the projected piston rod 35. Fixedly connected to the bracket 37 are a pair of chains 39 and 40 which correspond to the chains 29 and 30 heretofore described. The form of cylinder and associated parts shown in Figure 6 may be employed advantageously whenever it is unnecessary to limit the length of the cylinder due to lack of space.

It is thought that the many advantages of a power hoist curtain in accordance with this invention will be readily apparent, and although the preferred embodiments of the invention are as illustrated and described, it is to be understood that changes in the size, shape and arrangement of parts may be resorted to, so long as such changes fall within the scope of the invention as defined in the appended claims. While the invention is above described in connection with a locomotive cab, it is to be understood that the same may be employed in connection with any vehicle or the other structure for which the same is found to be applicable.

What I claim is:—

1. In an apparatus for winding a curtain on a drum to hoist the curtain, a pressure cylinder, a piston slidable within the cylinder and having a rod projecting therefrom, means operatively connecting the piston rod with the drum to provide for rotation of the drum upon movement of the piston, and means for admitting a pressure medium to one end of the cylinder to move the piston, said cylinder having an exhaust port adjacent but spaced from its opposite end to provide for the escape of excess pressure within the cylinder.

2. In an apparatus for winding a curtain on a drum to hoist the curtain, a pressure cylinder, a piston slidable within the cylinder and having a rod projecting therefrom, a support secured to the outer end of the piston rod, a shaft journaled in said support, a gear fixedly mounted on said shaft, a stationary rack having its teeth in mesh with said gear, means operatively connecting said shaft with said drum to provide for their rotation in unison, and means for admitting a pressure medium to one end of the cylinder to move the piston to rotate the gear, said cylinder having an exhaust port adjacent but spaced

from its opposite end to provide for the escape of excess pressure within the cylinder.

3. In an apparatus for winding a curtain on a drum to hoist the curtain, a pressure cylinder, a piston slidable within the cylinder and having a rod projecting therefrom, a bracket secured to the piston rod externally of the cylinder, a guide member slidably supporting said bracket, means operatively connecting said bracket with said drum to provide for the rotation of the drum upon movement of the piston, and means for admitting a pressure medium to one end of the cylinder to move the piston, said cylinder having an exhaust port adjacent but spaced from its opposite end to provide for the escape of excess pressure within the cylinder.

In testimony whereof, I affix my signature hereto.

20 JACK B. MAPLES.
